UNITED STATES PATENT OFFICE.

GEORGE F. ALEXANDER, OF WESTFIELD, MASSACHUSETTS.

LUMBER-DRYING MACHINE.

Application filed November 3, 1925. Serial No. 66,453.

My invention relates to improvements in machines used in the process of drying lumber, and consists generally of a carrier rotatable on a vertical axis, having top and bottom central openings, and divided into radial, open-ended compartments for the reception of the lumber to be dried, and certain peculiar supporting axial and peripheral supporting means, together with 5 suitable fastening or anchoring means for the lumber while being dried, humidifying means when needed, and such other parts and members as may be necessary or desirable in order to render the machine complete and 10 serviceable in every respect, all as herein-after set forth.

The primary object of my invention is to produce a comparatively simple yet highly efficient machine for drying lumber, by the 20 centrifugal action of air passing through the machine, thoroughly, and expeditiously, in a manner which prevents excessive checking, warping, twisting, and honeycombing, defects commonly found in ordinary kiln-dried lumber. The moisture content of the 25 lumber is expelled by the centrifugal force or action of the rotary carrier of the machine, that is to say, by the suction of air drawn outwardly between the courses of 30 lumber, whereby what may be termed a syphoning effect is produced in the pores of the lumber, due to the small amount of heat required, and the centrifugal movement which produces a pull of air on the surface 35 pores. Too fast drying may be counteracted by the use of moisture in the machine. By reversing the revolving carrier, as may be done as often as required in this machine, the lumber is dried on both sides alike, or, 40 in other words, the defects that result from drying lumber on one side faster than on the other are prevented from occurring.

A further object is to produce a lumber-drying machine through which the air is 45 caused to circulate at a velocity corresponding to the peripheral speed of the rotary carrier, the air entering through central openings at the top and bottom of said carrier, continuing inward from said top and bottom, and passing outwardly through the 50 drying compartments and between the courses of lumber piled therein, being finally expelled or discharged into the surrounding atmosphere.

55 This machine may be used in a heated

room, and then corresponds with a kiln, in which event the speed of the rotation of the carrier is lower than when said machine is used as an air drier.

A still further object is to provide the 60 machine with means for discharging into the top and bottom thereof, in the center, fine jets of live or exhaust steam, or of cold water, for the purpose of humidifying the air circulating through said carrier. The 65 moisture thus introduced into the carrier is carried by the air currents through the drying compartments in which the lumber is piled and through the piles thereof. This 70 moisture or humidity tends to equalize the drying process.

Another object is to provide the machine with convenient means for loading lumber into the same and securing it therein, and for releasing the lumber and unloading it 75 from the machine.

Still another object is to afford means for rendering the machine strong, stable, and durable, and capable of having rotary motion in either direction imparted to the carrier and load thereof, and with the proper amount of frictional resistance.

Other objects and advantages will appear in the course of the following description.

A preferred embodiment of the invention, 85 whereby I attain the objects and secure the advantages of the same, is illustrated in the accompanying drawings, and I will proceed to describe the invention with reference to said drawings, although it is to be understood that the form, construction, arrangement, etc., of the parts and members in 90 various aspects, are not material, and may be modified without departure from the spirit of the invention.

In the drawing, in which similar reference characters designate similar parts throughout the several views, Figure 1 is a top plan of one-half of a lumber-drying machine which embodies a practical form 100 of my invention, all except the left-hand portion of the roof being broken away to disclose the portions of the machine below which otherwise would be concealed, the right-hand portion of the supporting frame appearing in full, and there being disclosed in section, between these top and bottom portions, three drying chambers; Fig. 2, an enlarged end elevation of a fragmentary 105 portion of one of the lumber trucks and the 110

lumber piled thereon with open-work or perforated stickers between courses; Fig. 3, an enlarged sectional detail of a fragmentary portion of the frame of the carrier taken at the periphery; Fig. 4, a front elevation of said machine, portions of said frame being broken away and the supporting elements for such portions omitted; Fig. 5, a central, vertical section through said machine; Fig. 6, an enlarged, top plan of one-half of the central portion of the frame of the machine; Fig. 7, a central, vertical section through said frame at and adjacent to the axis thereof, and through the supporting members below, and, Fig. 8, a fragmentary, top plan of the main ball-bearing for the hub of the frame.

In the first view the ceilings over the three drying compartments therein appearing, two in full outline and one in partial outline, are omitted and the side walls of such compartments are in section; and in Fig. 5 means for supplying the machine with moisture or humidity are illustrated.

My machine may be supported and arranged to rotate on a central pier 1, and on a plurality of outlying piers 2 arranged equidistant apart and in a circle around said central pier. Only the upper portions of the piers 1 and 2 are shown. Mounted on and bolted or otherwise secured to the top of the pier 1 is a stirrup-bearing 3, and mounted on and secured to each of the piers 2 is a bracket 4 which affords bearings for a shaft 5 on which is a roller 6.

In the center of the stirrup-bearing 3 is a circular chamber 7, and fitting within said chamber is a hollow cylinder 8. Within the cylinder 8 are ball-case sections 9 which, when in place, form a complete cylinder that fits the inner wall or side of said cylinder 8, and is interiorly recessed to receive two sets of balls 10 at different elevations. The cylinder 8 has an interior flange at the bottom, and the ball-case sections 9 are shouldered at the bottom to receive said flange, as shown at 11. Thus the ball-case is supported a short distance above the bottom of the chamber 7. A plurality of radial bolts 12 may be provided to prevent the cylinder 8 from being raised off the bottom of the chamber 7, each of such bolts passing inwardly through the exterior portion of the stirrup-bearing 3 into engagement with the periphery of said cylinder. An axial member or hub 13 has an annular shoulder 14, and below said shoulder said hub is provided with a ball-cylinder 15 that is located in the ball-case (9) and against the periphery of which the balls 10 bear. In this manner is constructed a main ball-bearing for the frame of the carrier. The ball-cylinder 15 is rigidly secured to the hub 13 under the shoulder 14, and said ball-cylinder is not recessed to receive the balls 10, as are the sec-

tions 9, consequently the hub 13 is not locked down by means of said balls. Thus provision is made for the hub 13 to be raised in its bearing, under certain stresses and strains incident to the loading and unloading and operation of the machine without damaging the bearing members. The ball-case sections 9 are held in place from above by means of a ring 16 which is bolted or otherwise secured to the top of the cylinder 8 and extends inwardly over onto said sections.

Let into an annular channel 17 in the top of the stirrup-bearing 3, adjacent to the outer periphery thereof, and bolted or otherwise secured to said stirrup-bearing, is an annular ball-case 18 in which is a set of balls 19. Mounted on the balls 19 is a ball-case 20. The hub 13 has an overhanging head at the top, and the ball-case 20 is formed on the under side of such head. The ball-case 18 and 20 and the balls 19 constitute an auxiliary ball-bearing for the carrier frame. The aforesaid head of the hub 17 consists in part of a flange 21 above, in front of the ball-case 20 below, and in part of a plurality of radial arms 22 between said flange and ball-case. The arms 22 are spaced equidistant apart, and in the present example there are twelve of them, but this number may vary in different machines. Bolted or otherwise secured to the top of the hub 13 is a circular anchor-plate 23 having a central recess therein and provided with an inwardly-extending, annular flange 24.

Twelve I-beams or girders 25 are connected at their inner terminals with the arms 22 by means of lugs 26 and bolts 27 with nuts 28 thereon. The inner terminal portions of the lugs 26, in each pair are introduced between the flange 21 and the ball-case 20, and placed against opposite sides of one of the arms 22, and there secured by means of one of the bolts 27 with its nut 28, the bolt passing laterally through the lugs and arm. The inner ends of the lugs 26 bear against peripheral portions of the head of the hub 13 below the flange 21. The outer terminal portions of the lugs 26, in each pair, are riveted or otherwise secured to one of the girders 25 on opposite sides of the web thereof. In the present example the web on each girder 25 is thinner than the arm 22 with which said girder is connected, consequently it is necessary to insert filler plates 29 on opposite sides of said web and between the same and the lugs 26. Preferably the girders 25 are arranged at a slight upward inclination from within outwardly.

Riveted to the web on each side of each girder 25, adjacent to the outer end thereof, is an angle-iron or bracket 30, and riveted to said bracket is a channel iron 31, as clearly shown in Fig. 3. The channel-iron 31 encircles the girders 25 at their

outer ends, and is contiguous with such ends and with the parts of the brackets 30 to which said channel-iron is riveted, the inside of the latter being contiguous with the 5 girder ends and the laterally projecting parts of said brackets. Thus the channel-iron 31 forms the rim of the carrier frame. The girders 25 and the channel-iron or rim 31 are braced to strengthen the structure, 10 as shown at the right in Fig. 1. Ordinarily, the rim 31, because of its large size or circumference, is made in sections.

A circular I-beam 32, which ordinarily must be made in sections like the rim 31, is 15 riveted or otherwise secured to the under sides of the girders 25, a short distance in from said rim, and said I-beam is provided on the outside with a plurality of brackets 34. Each bracket 34 is riveted or otherwise 20 secured at the top against the bottom of one of the girders 25. The I-beam 32 forms a carrier or support for a circular rail 35 which is secured to the bottom of said support by means of clamps 36, these clamps 25 being arranged in pairs at intervals around said support and track. The clamps 36, in each pair, fit over the contiguous flanges on opposite sides of the support 32 and the rail 35, and bolts or rivets are passed through 30 contiguous portions of said clamps and flanges. The support 32 and the track 35 are of the proper combined depth to enable said track to bear and ride on the rollers 6 and maintain the girders 25 at the required 35 angle of inclination. When the hub 13 with its roller-bearing rotates in the stirrup-bearing 3, the track 35 travels around on the rollers 6. The rollers 6 have a slight downward inclination inwardly in order to compensate for the thrust of the track 35 which 40 is supported thereon, and carried by the support 32 which has a slight outward inclination from above downward.

The frame constructed in the manner just 45 described is well adapted to support and carry the load for which it is intended.

A cable 37 is given one or more turns around the rim 31 and carried around a driving pulley, as 38, being guided thereto 50 on one side by a sheave, as 39. When the driving pulley 38 is rotated, rotary motion is imparted, through the medium of the cable 37, to the frame and the superstructure, and load if any thereon and therein. The 55 rotary motion thus imparted may be in either direction. Any suitable motive power may be employed for driving the pulley 38; and the driving means may vary to meet different conditions.

60 There are twelve drying compartments in this machine, six long compartments, each indicated by the numeral 40, and six short compartments, each indicated by the numeral 41. These compartments are erected on 65 the frame and are radial to the axis of the

machine. Each long compartment 40 comprises a floor 42, parallel sides or partitions 43-43, and a ceiling 44; and each short compartment 41 comprises a floor 45, parallel partitions 46-46, and a ceiling 47. Rising 70 from every other girder 25, some distance from the inner end thereof, is an upright 48, and secured to the inner side of and rising above the rim 31, at intervals around the same, are uprights 49. There are other 75 uprights 50 and 51 which rise from the frame, the former being more nearly adjacent to the uprights 49 and the latter more nearly adjacent to the uprights 48. The floor 42, partitions 43, and ceiling 44, of each 80 compartment 40, extend inwardly from two adjacent uprights 49 to two adjacent uprights 48, and between two adjacent uprights 50 and two adjacent uprights 51. The floor 45, the partitions 46, and the ceiling 85 47, of each compartment 41, extend inwardly from the next two adjacent uprights 49, on either side of those just previously mentioned, between the next two adjacent uprights 50, on either side of the two just previously mentioned, and one of the aforesaid uprights 51 and the next adjacent upright 51 on the same side of the compartment 40, and beyond said last-named two uprights 90 51 to the sides 43 of the two compartments 95 40 on opposite sides of said compartment 41. The compartments 40 and 41 are open at both ends. Supported on the frame structure under the floor of each of the compartments 40 are parallel tracks or rails 52, and supported on the frame structure under the floor of each of the compartments 41 are parallel tracks or rails 53. The floor boards are between the rails in each compartment. The uprights are braced in the usual manner 100 to whatever extent may be necessary. A roof 54 is carried on rafters 55 which are supported on the uprights 48 and 49. In the center of the roof 54 is an opening 56, which opening is a little less in diameter 105 than is the distance from the axis of the machine to the inner end of any compartment 40. The frame of the machine opens around the hub 13 and between the girders 25 into the space in the superstructure beneath the opening 56. Thus is is seen that air can enter the center of the carrier from both the top and bottom thereof. The air, taken in to the center of the carrier, passes through the drying compartments, and is discharged 110 from the outer ends of said compartments, when said carrier is in motion. Thus the air surrounding the machine is caused to circulate through the same. The outer ends 115 of the triangular spaces between the compartments 40 and 41 are boarded on the outside.

The machine may be provided with some 120 means to humidify the same, as the sprayers illustrated in Fig. 5. These sprayers com- 125

prise a finely perforated, straight, horizontal pipe 57 above, and a finely perforated, annular pipe 58 below. The pipe 57 is connected with the down-turned terminal of a horizontal supply pipe 59, which latter is suitably supported over the top of the carrier, and extends downwardly in the axial center thereof, through the opening 56, far enough to locate said pipe 57 approximately on a level with the compartment ceilings 44 and 47. The pipe 59 is supported in any suitable manner and by any suitable means above the roof 54. The pipe 58 is carried on a plurality of posts 60 rising from a base 61 which encircles the pier 1, being located by said posts outside of or around the hub 13 and beneath the inner terminal portions of the girders 25. The discharge from the pipe 58 passes upwardly between the girders 25 into the open space in the center of the carrier. A horizontal supply pipe 62 has at its inner end an upturned part which is in open communication with the pipe 58.

When the carrier is rotated, air is drawn into the interior of the same at the center, some from above the same and some from below, and discharged through the compartments 40 and 41, as previously explained, and stream or water discharged from the sprayer pipes 57 and 58 commingle with the air in the center of said carrier, and passes with it through said compartments.

Material placed in the compartments 40 and 41, in such a manner as to permit the air to pass in contact therewith, is dried by the action of such air thereon.

When lumber in long pieces is to be dried, the same is usually placed on trucks which are run into the compartments 40 and 41 and there left until the lumber thereon is dry, when said trucks are withdrawn from said compartments, and the lumber is removed therefrom. The trucks for the compartments 41 are necessarily shorter than those for the compartments 40. In Fig. 4 I have shown the outer end of a long truck loaded with lumber in one of the compartments 40, and, in Fig. 5, the inner end of a long truck loaded in another compartment 40, and a side elevation of a short truck in one of the compartments 41. The long and short trucks just referred to are respectively designated by the numerals 63 and 63^a.

Each of the trucks 63 or 63^a is in the main of ordinary construction, and comprises a platform mounted on wheels which are adapted to run on the rails 52. The truck is provided with upright stakes 64 as usual, and lumber, such as the boards 65, may be stacked edgewise on the platform of the truck between said stakes, with perforated stickers, as 66, standing on end between the courses. A removable gate 67 which consists of a frame having a piece of coarse wire netting secured thereto, is provided for the

rear end of the truck. The gate 67 is provided near the bottom and adjacent to each vertical edge with two forwardly-extending lugs 68, and on each side of the truck 63, adjacent to the rear end thereof, is an outwardly-extending lug 69 which is receivable between said lugs 68. A pin 70 is passed down, through perforations in each set of lugs 68 and 69, when the gate 67 is in place, and thus secures said gate at the bottom to the truck. The gate is held securely in place at the top by means of a pair of rods 71 and a connecting turn-buckle 72 on each side of the truck and its load, said rods having their outer ends respectively connected at 73 with the truck and at 74 with said gate.

After the truck 63 has been loaded with the boards 65 arranged lengthwise and edge-wise thereon with the stickers 66 arranged at intervals between the courses of boards, the gate 67 is secured in place behind the boards, and the loaded truck is pushed into one of the compartments 40 or 41. The movement of any truck inwardly in its compartment is limited by means of an angle-iron stop 79, which is mounted on and secured to the radial girder 25 beneath the compartment, at the inner end thereof, and a stop bracket 80 on the front end of the truck, said stop being in the path of said bracket. When properly located in its compartment, the truck is secured by means of a pair of rods (as 75) and a connecting turn-buckle 76, the outer rod being connected at 77 with the truck at the front end, and the inner rod having at its forward terminal a hook 78 which is engaged with the flange 24 of the anchor-plate 23.

In a generally similar manner and by generally similar means the other trucks are loaded, close at their rear ends, run into their respective compartments, and secure in place therein.

Although the trucks stand at an incline in their compartments, the inclination being downward from circumference to center of the machine, there is no liability of the lumber shifting inwardly, as will be readily understood. Provision is made for carrying the trucks on an incline, as described, in order to reduce the tendency of said trucks to be projected from the carrier when the same is in motion, and for the further purpose of diverting the air currents from horizontal to upwardly directed courses, and thereby facilitating the movement of such currents and enhancing the action thereof on the lumber.

When all (preferably) of the compartments 40 and 41 have received loaded trucks, and said trucks have been fastened to the anchor-plate 23, the carrier is set in motion in one direction or the other, and by centrifugal force air is drawn in through the top

and bottom of said carrier at the center, and sucked out through said compartments and between the courses of lumber therein, passing through the stickers 66 and the perforated portions of the gates 67. The direction of rotation of the carrier is changed as and when required, so that the air currents shall be applied with equal force to both sides of the boards 65, or in a manner to 10 equalize or render uniform the drying process. Although the driving pulley 38 is so small in diameter, compared to the rim 31, and the carrier must in consequence travel very much slower than said pulley, 15 the speed of said carrier is sufficient to produce and maintain, throughout the drying operation, the required circulation of air through the drying compartments.

When the boards 65 are dry, the power 20 is shut off and the carrier comes to a standstill. The trucks are then unfastened and pushed out of their compartments, the gates 67 are released and removed, and the boards 65 with the stickers 66 are taken from the 25 trucks.

If, during the drying operation, it be necessary or desirable to humidify the air passing through the machine, steam or water is discharged through the spray pipes 57 and 30 58 into the carrier, as hereinbefore explained. The humidity prevents the surface of the lumber from drying faster than the interior portions thereof, and thus insures even or uniform drying.

The lumber may be arranged endwise and vertically instead of edgewise and horizontally on the trucks, in which event ordinary stickers, which comprise strips of wood each about one inch thick and from one to 40 two inches wide, are disposed at intervals horizontally between the courses, being supported in place by cleats tacked to the lumber, or by any other suitable means. Flat piling is not recommended, but can be resorted to by using open-work or perforated stickers, such as the stickers 66.

Squares of wood may be dried in this machine if properly stacked and separated by suitable stickers.

The loaded trucks, when fastened to the anchor plate 23 in the center of the machine, pull one against the other, and thereby greatly reduce the strain on the machine of the centrifugal throw or tendency to fly outwardly or be expelled from the carrier of 55 said trucks, when said carrier is revolved.

The heavy wire netting in the gates 67 prevents the lumber from sliding outwardly when the carrier is in motion, but does not appreciably interfere with the free flow of air through the loads.

The arrows in Fig. 5 indicate the directions of the air currents as they enter the machine from above and below at the center, 60 pass outwardly and radially through the

compartments, and escape from the outer ends of said compartments.

Owing to the necessarily small size of the stickers 66 illustrated in Figs. 4 and 5, no perforations are shown therein.

Although this machine is designed especially for drying lumber, it is conceivable that the same might be utilized for drying other materials, substances, or objects, such as fruit and vegetables, for example, hence 70 I do not desire or intend to limit myself in any way so far as the use of the machine is concerned.

What I claim as my invention, and desire to secure by Letters Patent, is:—

1. In a drying machine, of the class described, an unenclosed carrier rotatable on a vertical axis, and having an interior air intake and air outlets which communicate with said intake and discharge through the periphery of said carrier, and a supporting structure entirely underneath said carrier.

2. In a drying machine, of the class described, an unenclosed carrier rotatable on a vertical axis, and having an interior air intake and air outlets which communicate with said intake and discharge through the periphery of said carrier, a supporting structure entirely underneath said carrier, and 90 means to drive said carrier from its periphery.

3. In a drying machine, of the class described, an unenclosed carrier rotatable on a vertical axis, provided with radial compartments, and having therein a central air intake, said compartments being open at their inner ends to said intake, and opening at their outer ends through the periphery of said carrier, and a supporting structure 100 entirely underneath said carrier.

4. In a drying machine, of the class described, a carrier rotatable on a vertical axis, provided with radial compartments, and having therein an air intake which opens through the bottom around the axial center of said carrier, and with which said compartments communicate at their inner ends, said compartments opening at their outer ends 110 through the periphery of said carrier.

5. In a drying machine, of the class described, a carrier rotatable on a vertical axis, provided with a perforated bottom and a perforated roof, and with radial compartments, and having a central opening therein for the intake of air through said bottom and roof, said compartments being in open communication at their inner ends with said central opening, and opening at their outer ends through the periphery of said carrier.

6. In a drying machine, of the class described, an unenclosed carrier rotatable on a vertical axis, provided with radial compartments, and having a central opening therein for the intake of air, and with which 120

said compartments communicate at their inner ends, said compartments at their outer ends opening through the periphery of said carrier, supporting structure entirely underneath said carrier, and means to introduce moisture into said central opening.

7. In a drying machine, of the class described, a carrier rotatable on a vertical axis, provided with radial compartments, and having a central opening for the intake of air through the top, and with which said compartments communicate at their inner ends, said compartments opening at their outer ends through the periphery of said carrier, and means to introduce moisture into said central opening at the top thereof.

8. In a drying machine, of the class described, a carrier rotatable on a vertical axis, provided with radial compartments, and having a central opening for the intake of air through the top, and with which said compartments communicate at their inner ends, said compartments opening at their outer ends through the periphery of said carrier, and a sprayer introduced into said central opening through the top thereof.

9. In a drying machine, of the class described, a carrier rotatable on a vertical axis, provided with radial compartments, and having a central opening for the intake of air through the bottom, with which opening said compartments communicate at their inner ends, said compartments opening at their outer ends through the periphery of said carrier, and means to introduce moisture into said central opening at the bottom thereof.

10. In a drying machine, of the class described, a carrier rotatable on a vertical axis, provided with radial compartments, and having a central opening for the intake of air through the bottom, with which opening said compartments communicate at their inner end, said compartments opening at their outer ends through the periphery of said carrier, and a sprayer arranged to discharge moisture into said central opening at the bottom thereof.

11. In a drying machine, of the class described, a carrier rotatable on a vertical axis, provided with radial compartments, and having a central opening for the intake of air through the top and bottom, with which opening said compartments communicate at their inner ends, said compartments opening at their outer ends through the periphery of said carrier, and sprayers arranged to introduce moisture into said central opening through the top and bottom thereof.

12. In a drying machine, of the class described, a carrier rotatable on a vertical axis, provided with radial compartments, and having a central opening for the in-

take of air through the top and bottom, with which opening said compartments communicate at their inner ends, said compartments opening at their outer ends through the periphery of said carrier, a sprayer in said opening near the top thereof, and a sprayer located below said opening in position to discharge moisture into the same at the bottom.

13. The combination, in a drying machine of the class described, with an unenclosed carrier rotatable on a vertical axis, provided with radial compartments, and having a central air intake opening with which said compartments at their inner ends communicate, said compartments at their outer ends opening through the periphery of said carrier, and a supporting structure entirely underneath said carrier, of means to support objects to be dried in said compartments in a manner to permit air to pass between said objects.

14. The combination, in a drying machine of the class described, with a carrier rotatable on a vertical axis, provided with radial compartments, and having a central air intake opening with which said compartments communicate at their inner ends, said compartments opening at their outer ends through the periphery of said carrier, of trucks, for objects to be dried, receivable in said compartments, and central fastening means for said trucks, whereby the latter pull against each other under the strain incident to the centrifugal throw of the carrier when in motion.

15. The combination, in a drying machine of the class described, with a carrier rotatable on a vertical axis, provided with radial compartments, and having a central air intake opening with which said compartments communicate at their inner ends, said compartments opening at their outer ends through the periphery of said carrier, of trucks, for objects to be dried, receivable in said compartments, and means to fasten said trucks to a common center.

16. The combination, in a drying machine of the class described, with a carrier rotatable on a vertical axis, provided with radial compartments, and having a central air intake with which said compartments at their inner ends communicate, said compartments at their outer ends opening through the periphery of said carrier, of trucks, for objects to be dried, receivable in said compartments, and means to hold said trucks against the centrifugal force to which they are subjected when said carrier rotates.

17. The combination, in a drying machine of the class described, with a carrier rotatable on a vertical axis, provided with radial compartments, and having a central air intake opening with which said compartments communicate at their inner ends, said

- compartments opening at their outer ends through the periphery of said carrier, and an anchor-plate on the bottom in the center of said carrier, of trucks, for objects to be dried, receivable in said compartments, and means to fasten said trucks to said anchor-plate, whereby said trucks are held against outward displacement by the centrifugal force developed when the carrier is rotated, 5 the arrangement being such that opposite trucks pull one against the other and thereby reduce the strain of the centrifugal throw of the trucks on the carrier when the latter is revolving.
- 10 18. The combination, in a drying machine of the class described, with a carrier rotatable on a vertical axis, consisting in part of a supporting frame which inclines upwardly from the center, being provided with radial compartments, and having a central air intake opening with which said compartments communicate at their inner ends, said compartments at their outer ends opening through the periphery of said carrier, 15 of trucks, for objects to be dried, receivable in said compartments, and means to hold said trucks against the centrifugal force incident to the rotary motion of the carrier.
- 20 19. In a drying machine, of the class described, with a carrier rotatable on a vertical axis, consisting in part of a supporting frame which inclines upwardly from the center, being provided with radial compartments, and having a central air intake opening 25 with which said compartments communicate at their inner ends, said compartments at their outer ends opening through the periphery of said carrier, and means to rotate said carrier, the upward inclination of said frame tending to counteract the centrifugal force exerted on the contents of said compartments when said carrier is in motion.
- 30 20. The combination, in a drying machine of the class described, with a central support, and outlying supports, of a carrier consisting in part of a supporting frame provided with a central hub mounted to rotate in said central support, the peripheral portion of said frame travelling on said outlying supports, said carrier being provided with radial compartments, and having a central air intake opening with which said compartments communicate at their inner ends, said compartments opening at their outer ends through the periphery of said carrier, and means to rotate said carrier, said frame having an upward inclination from the center to counteract the centrifugal force exerted on the contents of said compartments when said carrier is in motion.
- 35 21. The combination, in a drying machine of the class described, with a suitably supported stirrup-bearing having a central recess therein, an anti-friction bearing in said recess, and outlying supports, of a carrier consisting in part of a frame having a central head-provided hub mounted to rotate in said anti-friction bearing, and having its peripheral portion supported on 40 said outlying supports, said carrier being provided with radial compartments, and having a central air intake opening with which said compartments communicate at their inner ends, said compartments opening at their outer ends through the periphery of said carrier, and an anti-friction bearing between the peripheral part of the top of said stirrup-bearing and the head of said hub.
- 45 22. The combination, in a drying machine of the class described, with a suitably supported stirrup-bearing having a central recess therein, and anti-friction bearing in said recess, and a plurality of suitably mounted outlying rollers, of a carrier consisting in part of a frame having a central hub mounted in said anti-friction bearing, and provided adjacent to its periphery with a track which rides on said rolls, said hub having an overhanging head, an anti-friction bearing between said stirrup-bearing and said head, said carrier being provided with radial compartments, and having a central air intake opening with which said compartments communicate at their inner ends, said compartments at their outer ends opening through the periphery of said carrier.
- 50 23. In a drying machine, of the class described, a frame comprising a hub having a projecting head, said hub being adapted to be mounted for rotation, radial girders, means to secure said girders to said head, a member encircling and secured to said girders at their outer ends, an annular support secured to said girders underneath and adjacent to their outer ends, an annular rail secured to said support, and a superstructure on said frame, divided into radial compartments, and having therein a central air intake opening with which said compartments communicate at their inner ends, said compartments at their outer ends opening through the periphery of said superstructure.
- 55 24. In a drying machine, of the class described, a frame comprising a hub having a projecting head, said hub being adapted to be mounted for rotation, radial girders inclined upwardly from the head of said hub, means to secure said girders to said head, a member encircling and secured to said girders underneath and adjacent to their outer ends, an annular rail secured to said support, and a superstructure on said frame, divided into radial compartments, and having therein a central air intake opening with which said compartments communicate at their inner ends, said compartments at their outer ends opening through the periphery of said superstructure.

partments at their outer ends opening through the periphery of said superstructure.

25. In a drying machine, of the class described, a frame comprising a central member, a plurality of radial girders extending from said member, and a channel member, for a driving cable, encircling and secured to said girders at their outer terminals, supporting means for said central member and the peripheral portion of said frame, and a superstructure on said frame, divided into radial compartments, and having a central air intake opening with which said compartments communicate at their inner ends, said compartments at their outer ends opening through the periphery of said superstructure.

26. In a drying machine, of the class described, an unenclosed carrier rotatable on a vertical axis, and having a roof, floors, and partitions dividing said carrier into radial compartments, the central portion of said carrier being open, and said compartments communicating at their inner and outer ends respectively with the central opening in said carrier and the outside atmosphere, and a supporting structure entirely underneath said carrier.

27. In a drying machine, of the class described, an unenclosed carrier rotatable on a vertical axis, and having a roof, floors, partitions, and ceilings dividing said carrier into radial compartments, the central portion of said carrier being open, and said compartments communicating at their inner and outer ends respectively with the central opening in said carrier and the outside atmosphere, and a supporting structure entirely underneath said carrier.

28. The combination, in a drying machine, with a carrier rotatable on a vertical axis, provided with radial compartments, and having a central air intake opening with

which said compartments communicate at their inner ends, said compartments at their outer ends opening through the periphery of said carrier, of trucks receivable in said compartments, each of said trucks being provided at the outer end with means to prevent outward displacement of the objects piled thereon, but permitting the free passage of air therethrough, and means to secure said trucks in place in said compartments.

29. The combination, in a drying machine, with a carrier rotatable on a vertical axis, provided with radial compartments, and having a central air intake opening with which said compartments communicate at their inner ends, said compartments at their outer ends opening through the periphery of said carrier, of trucks receivable in said compartments, means to secure said trucks in place in said compartments, and perforated stickers adapted to separate lumber arranged in courses on said trucks, whereby air may pass freely between said courses.

30. The combination, in a drying machine, with a carrier rotatable on a vertical axis, provided with radial compartments, and having a central air intake opening with which said compartments communicate at their inner ends, said compartments at their outer ends opening through the periphery of said carrier, of trucks receivable in said compartments, each of said trucks being provided at the outer end with means to prevent outward displacement of the objects piled thereon, but permitting the free passage of air therethrough, means to secure said trucks in place in said compartments, and perforated stickers adapted to separate lumber arranged in courses on said trucks, whereby air may pass freely between said courses and out through said securing means at the outer end of the truck.

GEORGE F. ALEXANDER.
